UNITED STATES PATENT OFFICE.

PLIMMON H. DUDLEY, OF NEW YORK, N. Y.

RAILWAY-SLEEPER.

SPECIFICATION forming part of Letters Patent No. 327,667, dated October 6, 1885.

Application filed May 22, 1885. Serial No. 166,366. (No model.)

To all whom it may concern:

Be it known that I, PLIMMON H. DUDLEY, of the city, county, and State of New York, have invented a new and useful Improvement 5 in Railway-Sleepers, of which the following is a specification.

My invention relates to that class of sleepers or supports for the rails of railways, which consist of a metallic sleeper or bowl placed below the rail and an elastic block of wood or other yielding material seated upon the metallic sleeper or bowl and forming the direct support of the rail.

The invention consists in novel features of 15 construction and combinations of parts, which are hereinafter described, and pointed out in the claims.

In the accompanying drawings, Figure 1 is an elevation of a sleeper embodying my invention and two rails supported thereon. Fig. 2 is a vertical section in a plane parallel with Fig. 1. Fig. 3 is a transverse section on the plane of the dotted line $x-x$, Fig. 1, but illustrating a modification of the invention. Fig. 25 4 is a longitudinal section of a sleeper or bowl which is of a length to support two blocks; also showing two rails supported thereon. Fig. 5 is a sectional view similar to Fig. 4, but showing the sleeper of a length to hold three 30 blocks. Fig. 6 is a transverse section of two track-rails and two separate bowls and blocks supporting them, the two rails and sleepers or bowls being tied together to prevent spreading of the track. Figs. 7 and 8 are sectional 35 views of bowls and blocks embodying slight modifications of my invention. Fig. 9 is a perspective view of one of the wood or other blocks which I may employ, and Fig. 10 represents one of the bolts which are employed 40 for clamping the rails in place.

Similar letters of reference designate corresponding parts in all the figures.

In all cases A designates the rails, and B designates the bowls or bosses, which may be 45 made singly, and each support a block, C, of wood, as shown in Figs. 1, 2, and 3, or which may be made of a length to support two or more blocks each, as shown in Figs. 4 and 5. Each of the bowls or sleepers B has, as here 50 represented, a downwardly-flaring base portion, b, which may be straight or curved, and

which has, preferably, at its outer edge, a downwardly-turned rim, b'.

In the form of my invention shown in Figs. 1, 2, and 3, the bowls B each support a single block C, and are constructed with an upwardly-projecting box or casing, b², forming a socket to receive and confine the block C. This block and the box or casing may be rectangular, as here shown, or of other form, and the box or 55 casing has at opposite sides lugs or ears b*, as shown in Figs. 1 and 3. The rails A rest upon the blocks C, and are there held by clamps c, which are constructed to bear upon the flange of the rail, as shown best in Fig. 3, and 60 to rest upon the top of the box or casing b². These clamps c are held in place by bolts D, which, as shown in Figs. 1 and 3, pass through 65 the base b of the bowl B and through the lugs or ears b*, and are provided at their lower 70 ends with heads d and at their upper ends with nuts d'. The heads d of the bolts D are of peculiar construction. They have a greater projection on the sides which are remote from the box b² and a less projection on the sides of 75 the bolts adjacent to the box b².

The holes * in the base portion b through which the bolts D are passed are elongated in a direction away from the box b², and when the nuts d' have been removed and the bolts 80 slipped down to free them from the ears b*, they may, if swung outward, as shown by dotted lines in Fig. 3, be removed from the holes *, the heads d being no wider than the bolts, as will be seen from Fig. 10. The holes * may 85 then be utilized to introduce sand or other ballast into the bowl or sleeper B, or a small tamping-bar may be introduced through them for ramming down the ballast. This 90 may be done and the track surfaced without removing the block C from its box or socket.

The bowl or sleeper B (shown in Fig. 2) has the box portion or block-socket b² formed with a solid bottom, b³; but the form of sleeper shown in Fig. 3 has a false or loose bottom, b³*, which 95 rests upon flanges or rests provided within the box or socket, and may be removed when the block C is not in place, in order to permit the introduction of ballast within the bowl.

In the examples of my invention shown in Figs 1, 2, and 3 the four sides of the box or 1: socket b² are complete and continuous, and

the block C can only be removed by lifting it bodily upward and out of the box or socket.

Turning now to Figs. 4 and 5 it will be seen that the bowls or sleepers B are constructed to support more than one block C, the sleeper shown in Fig. 4 being adapted to support two blocks, and that shown in Fig. 5 three blocks.

In Figs. 4 and 5 the blocks C are each surrounded by a metal band, C', which may be driven upon it, as shown in Fig. 9, and prevents the splitting of the block.

In the examples shown in Figs. 4 and 5 the box or socket for the block C is open on two sides, and on those sides there is only a slight lip or rib, b⁴, which retains the block in place laterally, and also serves to hold the false bottom b^{3*} in place. The block with its band rests in the seat provided for it on the false bottom b^{3*}, and the rails A are supported on the blocks and there secured by clamps and bolts like those before described.

I have represented the long sleepers or bowls B (shown in Figs. 4 and 5) as provided with cross-partitions b⁵, which prevent water from running and guttering under the sleeper when laid on a gradient, and which also prevent the sleeper from working in the direction of traffic or downward when laid on a steep gradient. These partitions also serve to strengthen the sleepers or bowls, and may be at right angles to the top thereof, as shown in full lines, or inclined, as shown by dotted lines in Fig. 4. The lower profile of the partitions b⁵ will be seen from Fig. 6, to which I now refer.

In Fig. 6, which is supposed to be a transverse section of two track-rails supported by sleepers such as are shown in Fig. 5, are represented bolts D and clamps e, for holding down the rails, similar to those shown in Fig. 3.

As the boxes or block-sockets b² (shown in Fig. 6) are supposed to be open on one or both sides, which are transverse to the length of the rail, I have represented the rails A as tied together by a cross-rod or stretcher, E, the ends of which form clamps e, and are secured by the bolts D. The cross rod or tie E may have an I-shaped, T-shaped, or other suitable transverse section, or may consist simply of a flat bar or a round rod. It may be secured at its ends to the rail flange or web independently of the bolts D, and separate clamps e, such as are on the outer side of the rail, may be used on the inner sides thereof.

The construction shown in Fig. 7 is like that shown in Fig. 3, save that the bolts D' do not extend through the base portion b of the sleeper or bowl B, as do the bolts D, but simply pass through the lugs or ears b*. The rail is held by clamps e, secured by the bolts D', as before described.

In the example of my invention shown in Fig. 8, I have shown a bowl or sleeper B having at the top a block seat or rest formed by slight ribs or flanges b⁴, within which is a false bottom b^{3*}, and which confine in place the block C. In this form of the invention the block C has a band, C', around its upper

portion, and this band has ears b*, through which pass the long bolts D, which pass through holes * in the sleeper or bowl B, as before described, and hold the rail-clamps e in place.

The band C' is permanently secured upon the block C by driving it on or otherwise, and hence serves to more closely confine and sustain the block than could the box-like portion of the sleeper, in which the block is loosely fitted to permit of its ready removal therefrom. Fig. 9 shows a similar band, C', surrounding the block C at about the middle 80 of its height, and having lugs or ears b* for the reception of holding-down bolts.

In all the examples of my invention the base portion of the sleeper and its box portion which forms the block-socket may be of 85 wrought or cast metal, and made separately or formed integral; hence it will be seen that the principal part of the sleeper is of indestructible material, and the wood block is protected and confined so as to avoid splitting 90 or crushing. The employment of the false bottom in the block-seat is very desirable, because when it is removed a large opening is afforded, through which ballast may be introduced and rammed down within the sleeper. 95

It will also be seen that while the elongated holes * and elongated bolt-heads d afford facility for removing the bolts when desired, there is no danger of the bolts failing to hold when the nuts d' are tightened, because the 100 heads d have a tendency to slide upward on the inclined under side of the sleeper B, which brings the bolts into those ends of the slots * which are nearest the rail, and causes their heads to lap on the under side of the sleeper 105 at each end of the slots *.

When the box or block-socket is not complete on all four sides, the block can be readily removed laterally without removing the rail, and the false bottom b^{3*} can then be 110 removed to enable more ballast to be introduced. A longer or shorter block can then be inserted in the place of the one removed; hence it will be seen that great facility is afforded for surfacing the track as may be necessary, and it may be done by introducing sand into the bowls by placing small shims or plates of metal under the rails or by inserting longer blocks, and without disturbing the ballast. 115

In lieu of employing blocks C of wood, I may employ blocks of other elastic or yielding material, which will, like wood, absorb and diminish the shock produced by the passage of trains over the track.

I have not represented any fastenings for the joints between the rails, as such fastenings form no part of my invention. I may employ fish-plates or any other well-known or suitable fastenings.

The sleepers or bowls will usually be buried in ballast above their flaring base portions b, and nearly to the top of the box portions or block-sockets b². I have here omitted the

ballast in order to show more clearly the parts to which my invention relates.

What I claim as my invention, and desire to secure by Letters Patent, is—

- 5 1. The combination, with a metallic sleeper or bowl, of an elastic block to be seated on the sleeper or bowl to form a support for the rail, and a metal band independent of the sleeper or bowl, permanently secured upon 10 and encircling and closely confining the block, substantially as herein described. 40
- 15 2. The combination, with a metallic sleeper or bowl and a railway-rail, of an elastic block seated upon the sleeper or bowl and supporting the rail, a band independent of the sleeper or bowl surrounding the block and provided with laterally-projecting lugs or ears, clamps for engaging the base-flange of the rail, and bolts connecting the sleeper or bowl and clamps 20 and passing through the lugs or ears on the said band, substantially as herein described. 45
- 25 3. The combination, with a metallic sleeper or bowl having a block-seat at the top and a removable or false bottom fitted to said seat, of an elastic block seated on the sleeper or bowl to form a support for a railway-rail, substantially as herein described. 50
- 30 4. The combination, with a metallic sleeper or bowl having at the top a block-seat surrounded by upwardly-projecting flanges or ribs, of a removable or false bottom fitted within the flanges or ribs and by them confined laterally, and an elastic block seated within the flanges or ribs and also held laterally in place thereby, substantially as herein described. 55
- 35
5. The combination, with a railway-rail and an elastic block supporting the same, of a metallic sleeper or bowl having at the top a block-seat and having its base portion flaring or inclined downward and outward away from the block-seat, and also having on the concave under side a downwardly-projecting partition or flange which extends transversely to the length of the sleeper or bowl and to the line of the rail, substantially as herein described. 45
6. The combination, with the rails A, of the metallic sleepers or bowls B, placed below the rails, the blocks C, seated on the sleepers or bowls and supporting the rails, and a cross-bar or tie-rod, the ends of which form clamps bearing on the base-flanges of the rails, and are secured to the sleepers or bowls, substantially as herein described. 50
7. The combination, with a metallic sleeper or bowl having at the top a block-seat and slots extending in opposite directions from said seat, of a block in said seat, a rail supported on said block, clamps for securing the rail, and bolts D, for securing said clamps passing through the slots in the sleeper or bowl, and having elongated heads d, which may be withdrawn from said slots when the bolts are tilted outward into an inclined position, substantially as herein described. 60
